BEAUTICIAN'S POLE

Alfredo C. Loa, 854 Vancura Drive, Corpus Christi, Tex.

Filed Feb. 2, 1962, Ser. No. 68,626

Term of patent 14 years

(Cl. D1—12)

Fig. 1

Fig. 2

Fig. 3

FIG. 1 is a front perspective view of a beautician's pole showing my new design;

FIG. 2 is a rear perspective view; and

FIG. 3 is a top plan view.

Two of the narrow sides of the beautician's pole are shaded to indicate a contrast of color, and the curved shading on the wide sides represents a surface pattern.

The dominant features of my design reside in the full line portions of the drawing.

I claim:

The ornamental design for a beautician's pole, as shown and described.
